UNITED STATES PATENT OFFICE

2,035,099

REPRODUCING APPARATUS

Theodore J. Smulski, Gary, Ind.

Application September 10, 1934, Serial No. 743,378

12 Claims. (Cl. 33—23)

This invention relates to a reproducing apparatus and has special reference to a construction of the pantographic type for reproducing patterns of a template on a desired surface in an enlarged or reduced state or in some translated form thereof.

More particularly this invention relates to reproducing apparatus comprising a base slidable over a surface having a pattern-carrying template mounted thereon and a pantograph including a fixed bearing on the base and linkage mechanism supported thereby and extending therefrom, the linkage mechanism carrying a tracing point for moving over the pattern-carrying template and another tracing point controlled by the first mentioned tracing point for making a copy of the pattern on the surface over which the base slides.

The present invention contemplates the provision of a reproducing apparatus in which all of the elements necessary for completing the reproduction of the pattern are contained in a single unit or are mounted in a unitary manner on a single base. The base is slidable over a surface and is preferably held in a given plane by a straight edge against which an edge of the base may rest, the pantographic mechanism mounted on the base marking a copy of the pattern on the surface from a template likewise mounted on the base. It is usual, insofar as applicant is aware, to provide templates which are separate and apart from the pantographic mechanism and which, besides being relatively cumbersome and awkward to manipulate, are more costly than that construction contemplated by the present invention.

The present construction is compact in form and simple to operate and is capable of reproducing any pattern in an extended or condensed condition or inclined in either direction with but simple adjustments of the pantographic mechanism.

One of the objects of the present invention is to provide a reproducing apparatus of the character indicated above which is simple in operation and construction, is comparatively inexpensive to manufacture and is durable.

Another object of this invention is to provide a reproducing apparatus of the type above noted in which all of the elements entering into the construction for the complete reproduction of a desired pattern form a unitary device.

A further object of this invention is to provide a reproducing apparatus as hereinbefore pointed out whereby the reproduction may be ex-

tended or condensed or may be inclined or reproduced in some translated form.

Other objects and advantages will hereinafter be more particularly pointed out, and for a more complete understanding of the characteristic features of this invention reference may now be had to the following description when read together with the accompanying drawings, in which latter—

Figure 1 is a plan view of an apparatus embodying the features of this invention;

Fig. 2 is a view similar to Fig. 1 with the template and a tracing point thereof removed;

Fig. 3 is a side elevational view of Fig. 2;

Fig. 4 is a central, vertical sectional view taken on the line 4—4 of Fig. 2;

Fig. 5 is a diagrammatic view similar to Fig. 2 showing an initial position of the elements in full lines and a changed position thereof in dotted lines;

Fig. 6 is a view similar to Fig. 5 with the elements thereof changed to extend the reproduction and to incline the same in a different direction from that shown in Fig. 5, the elements being shown in an initial position in full lines and in a changed position in dotted lines; and

Fig. 7 is a view illustrative of the character of some of the reproductions possible from the apparatus embodying the features of this invention.

Referring now more particularly to the drawings, the device of this invention is shown as being embodied in a base 10 preferably formed of sheet metal of channel cross section when viewed from one end thereof, the legs 10^a and 10^b of the channel member providing bearing surfaces 35 on which the plate rides in its movement over the surface upon which the pattern is to be reproduced. The base is indicated as being made of sheet metal, although of course it is to be understood that any substantially rigid material may be so employed consistent with the purposes for which it is intended.

The base is provided with a template 11, for carrying the pattern which, in the present instance, is shown as the letters of the alphabet 45 together with the necessary numerals disposed in contiguous zones. The characters of the template are preferably cut into the face thereof, and the grooves thus formed are of sufficient width to permit a stylus or other like instrument 50 to slidably engage therewith. It is, of course, to be understood that various patterns may be cut into the pattern-carrying template 11 and that this invention is not to be confined to its use in reproducing the characters specifically 55

shown. The template 11 is held in a fixed relation to the face and is spaced therefrom, the plate being held in such spaced relation by the vertically extending posts 12. It is desirable to have the template 11 removable so that it may be replaced by a template carrying a different pattern.

5 A tracing point 13 is slidably mounted over the face of the template, the tracing point carrying 10 a plurality of apertures 14 for registration with the grooves of the pattern to be reproduced. In the present instance there is one aperture for each of the numerals or letters to be reproduced, each of the apertures having sufficient movement 15 to be capable of outlining its respective character or zone. The tracing point is preferably formed of sheet metal and is cut out in such a manner as to disclose therethrough the characters of pattern for reproduction, although, of course, it is to be understood that the same function 20 may be performed by various types of tracing points which in some cases may need be no more than a single pin.

An arm 15 is mounted on the base for slid- 25 able movement sidewise thereof, the arm having an enlarged head portion 16 and a reduced shank portion 17. Opposite sides of the enlarged head portion are preferably guided in a sidewise direction by guide rollers 18, which in the present 30 instance are rotatably mounted on the upright posts 12, the guide rollers preferably having circumferential grooves in which the sides of the enlarged head portion ride in a spaced relation from the base.

35 The enlarged head portion 16 is provided with a shouldered recess 19 for receiving a circular disc 20, the circular disc having a finger-piece 21 extending from a circumferential portion radially of the disc for purposes of manual adjustment. The disc 20 is preferably removably held in position on the shoulder of the recess 19 by a cover plate 22 which is secured to the top of the 40 slidable arm 15 by screws or other similar means, the securing plate 22 being preferably of spring material to permit a rotatable movement of the disc 20 against the tension of the spring plate 22.

The circular disc 20 is provided with an elongated slot 23 extending through the disc radially thereof. The position of the radially extending 50 slot 23 concerns the inclination of the reproduction and will be explained in greater detail hereinafter. In order to predetermine the inclination of the reproduction it is preferable to employ a graduation about the periphery of the 55 shouldered recess so that the disc 20 may be set prior to the completion of the reproduction. The slot 23 in the present instance is shown as being straight although the location and character of slot may be changed in accordance with the 60 character of translation desired. An arcuate, tortuous or other slot may give a novel appearance to the reproduction of any pattern so that the present disc 20 may be replaced by another disc having a preferred form of slot.

65 The shank end 17 of the movable arm 15 is pivotally connected to an arm 24, the latter arm being pivotally connected at one end thereof to a post 25 fixedly mounted on the base 10. The arm 24 is one of a pair of cooperating arms ex- 70 tending in a substantially forwardly and rearwardly direction, the other arm of which is indicated by the numeral 26. One end of the arm 26 is pivotally connected to the base by a rivet 27 or other securing means in a fixed position 75 on the base, and the inner free ends of the arms

24 and 26 are slidably connected by means of a connector 28 having movement along the arm 24 to any fixed adjusted position thereon by the thumb nut 29. The connector 28 is provided with a roller 30 pivoted to an ear extending therefrom, which roller engages a track formed by the arm 26 of channel cross section. Movement of the connector 28 in either direction will lengthen or shorten the pivotal movement of the cooperating arms 24 and 26 to determine the 10 amount of sidewise movement of the arm 15, as will hereinafter be more fully pointed out.

15 The free end of the arm 26 is pivotally connected to the end of an arm 31 which extends sidewise of the base, the other end of the arm 15 20 31 being pivotally connected to an arm 32 extending substantially parallel with the arm 26 and being preferably of the same length. The arm 32 is pivoted at its other end to the base 10 by a rivet 33 or other securing means. The arm 20 31 is provided preferably with an integrally formed arm portion 34 extending in a forwardly and rearwardly direction upon the end of which is pivoted an arm 35 extending in a direction across the width of the apparatus. An arm 36 25 30 cooperating with arm 35 is pivoted on the arm 31 and extends in the same direction and preferably parallel with the arm 35, the pivotal points for the arms lying in the same plane and having threaded pins 37 at the opposite free ends for pivotal connection with the tracing point 13. The plate forming the tracing point 13 is provided with extensions on each side thereof for receiving the pins 37, and the plate is suitably held in position by the threaded caps 38. The arms 35 35 and 36 are tied together for equal and simultaneous movement by means of an arm 39 extending to be pivotally connected adjacent the outer free ends thereof, the arms therefore being capable of universal movement in a single plane 40 since they are pivotally mounted to move forwardly and rearwardly on an arm which is slid- 45 able in a sidewise direction.

50 A pair of horizontally extending cooperating arms 40 and 41 are disposed on the base, one end 45 of the arm 41 being pivotally connected to the post 25, which latter is fixed to the base, and the other free end being pivotally connected to an arm 42 extending in a forwardly and rearwardly direction. The arm 40, in turn, is pivotally connected at its outer end to the base 10 by means of the rivet 43, or an equivalent securing means, an inner portion of the arm 40 together with an inner portion of the arm 41 being slidably and adjustably connected together through a connector 44. The other end of arm 40 is pivotally connected to one end of a link 39^a, the other end of link 39^a being adjustably connected to arm 39 at a predetermined position thereof. The connector 44 is preferably slidable on the arm 41 60 and may be fixed in any predetermined position thereon by means of the nut 45, the connector 44 having an ear extending therefrom upon which a roller 46 is disposed for engaging a track or guideway formed by the channel cross section of the arm 40. An adjustment of the connector 44 will operate to determine the size of the reproduction as to the height thereof, a movement in one direction condensing or reducing the height 65 of the reproduction and a movement in the other direction extending or enlarging the reproduction.

70 One end of the arm 42 is pivotally connected to the free end of the arm 41, as hereinabove stated, the other end of the arm 42 carrying a 75

reproducing point 47 for making the copy of the pattern on the surface. This tracing point may be of any desired character, either a colored lead or a container for ink or other marking fluid.

5 Intermediate the ends of the arm 42 is positioned a pin 48 for engaging the slot 23 and extending therethrough to project beyond the bottom thereof.

The pin 48 depends from the arm through the slot 23 for engagement with the upper surface of a presser bar 49, the latter bar being fixed at one end and being preferably formed of spring material normally bowed to extend in a spaced-apart relation from the base at an intermediate portion engaged by the pin 48. However, in operating the reproducing apparatus to permit the reproducing point 47 to engage the surface, the presser bar is moved downwardly in a direction toward the base preferably by the finger striking the presser bar at the end designated by the numeral 50, the pin 48 normally being held upwardly with the reproducing point 47 out of engagement with the surface before pressure is applied to the presser bar.

25 In the operation of the reproducing apparatus, the character or pattern to be reproduced is selected and the stylus or other operating instrument is inserted into the aperture corresponding to such character, the stylus passing through the aperture into the groove defining the character and being guided thereby. The movement of the tracing point operates the cooperating arms 40 and 41 during a movement thereof in a forward and rearward direction and operates 30 the cooperating arms 24 and 26 during movement thereof in a sidewise direction. The arm 42 carrying the second tracing point is, in turn, operated by the forwardly, rearwardly and sidewise movements just recited to guide the movement 35 of the tracing point over the surface receiving the reproduction.

The reproduction may be either extended or condensed or may be inclined as desired by reason of the adjustments hereinbefore noted. 45 For example, a movement of the connector 28 in one direction may reduce the width of the character to be reproduced to an extent such that it may be substantially smaller than the character of the template, or if the connector 28 be moved in an opposite direction the reproduction 50 may be greater in width substantially than the character of the template. Likewise should the connector 44 be moved in one direction the reproduction may be considerably less in height 55 than that of the original character of the template, or if the template be moved in the opposite direction the height of the character may be considerably greater than the character of the template. The range of reproduction may 60 be substantially from a point to any desired height and width consistent with convenience in use. Also by means of rotating the disc 20, the diametrically disposed slot 23 may translate the movement of the pantographic mechanism so that 65 the characters or reproduction as a whole are inclined or otherwise formed with respect to the original of the template. The forms of reproduction are illustrated in Fig. 7, and the adjustment as to the height and width of the reproduction is illustrated in the diagrammatic show- 70 ings in Figs. 5 and 6.

75 While but a single embodiment of this invention is herein shown and described it is to be understood that various forms thereof may be apparent to those skilled in the art without de-

parting from the spirit and scope of this invention, and therefore the claims hereof are to be limited solely by the prior art and the scope of the appended claims.

I claim:

1. A reproducing apparatus comprising a base 5 slidable over a surface, a template having a plurality of individual patterns thereon and mounted on said base, a pantograph including a fixed bearing on said base, linkage mechanism supported thereby and extending therefrom carrying a tracing member for moving over said template, said tracing member having separate means for cooperation with each of said individual patterns, and a reproducing point controlled by said tracing member for making a copy of a selected pattern on said surface.

2. A reproducing apparatus comprising a base 10 slidable over a surface, a template having a plurality of individual patterns thereon and mounted on said base, and a pantograph including a fixed bearing on said base, adjustably connected arms extending therefrom for predetermining the size of the reproduction, a tracing member carried by one of said arms for moving over said 15 template, said tracing member having separate means for cooperation with each of said individual patterns, and a reproducing point carried by another of said arms and controlled by said tracing member for making a copy of said pattern on said surface.

3. A reproducing apparatus comprising a base 20 slidable over a surface, a template having a plurality of individual patterns thereon and mounted on said base, and a pantograph including a 25 fixed bearing on said base, adjustably connected arms extending therefrom for predetermining the size of the reproduction, a tracing member carried by one of said arms for moving over said template, said tracing member having separate 30 means for cooperation with each of said individual patterns, a reproducing member carried by another of said arms and controlled by said tracing point for making a copy of said pattern on said surface, and adjustable means for connection with one of said arms for controlling the 35 angularity of the reproduction.

4. A reproducing apparatus comprising a base 40 slidable over a surface, a template comprising a plate having a plurality of individual depressed 45 portions forming characters, said template being mounted on said base, and a pantograph including a fixed bearing on said base and linkage mechanism supported thereby and extending therefrom carrying a tracing member, said tracing member comprising a plate having an aperture for alignment with the individual depressed portion of each of said characters and a reproducing point controlled thereby for making a 50 copy of said character on said surface. 60

5. A reproducing apparatus comprising a base 55 slidable over a surface, a template having a plurality of individual patterns thereon and mounted on said base, a tracing member for free movement over said template, said tracing member 65 having separate means for cooperation with each of said individual patterns, an arm mounted for slidable movement sidewise of said base, a pair of cooperating arms extending in a forwardly and rearwardly direction having their outer ends piv- 70 otally connected to said base and their inner portions connected together and to said movable arm for predetermining the width of the reproduction, a pair of cooperating arms extending sidewise of said base having their outer ends piv- 75

totally connected to said base and their inner portions connected together for predetermining the height of the reproduction, a reproducing point for making a copy of said pattern on said surface, and a substantially forwardly and rearwardly extending arm carrying said reproducing point and being slidably connected to said cooperating arms having sidewise movement and pivotally connected to said arms having forward and rearward movement, said tracing member operating all of said arms in accordance with the selected pattern to be reproduced.

6. A reproducing apparatus comprising a base 15 slideable over a surface, a template having a plurality of individual patterns thereon and mounted on said base, a tracing member for free movement over said template, said tracing member having separate means for cooperation with each of said individual patterns, an arm mounted for 20 slidable movement sidewise of said base, a pair of cooperating arms having forward and rearward movement and having their outer ends pivotally connected to said base and their inner portions adjustably connected together and to said 25 horizontally movable arm for predetermining the width of the reproduction, a pair of cooperating arms having sidewise movement and having their outer ends pivotally connected to said base and their inner portions adjustably connected together for predetermining the height of the reproduction, a reproducing point for making a copy of said pattern on said surface, and an arm having forward and rearward movement for carrying said reproducing point and being connected to said cooperating arms having sidewise movement and to said arms having forward and rearward movement, said tracing member operating all of said arms in accordance with the pattern to be reproduced.

40 7. A reproducing apparatus comprising a base slideable over a surface, a template having a plurality of individual patterns thereon and mounted on said base, a tracing member for free movement over said template, said tracing member having separate means for cooperation with each of said individual patterns, an arm mounted for 45 slidable movement sidewise of said base, linkage mechanism connecting said tracing member and said movable arm, a reproducing point for 50 making a copy of said pattern on said surface, an arm carrying said tracing member, and linkage mechanism connecting said tracing member and said reproducing point for translating forward and rearward movement of said tracing member 55 to said reproducing point, said movable arm having sidewise movement being connected to said second tracing member arm for the sidewise movement thereof.

8. A reproducing apparatus comprising a base 60 slideable over a surface, a template having a plurality of individual patterns thereon and mounted on said base, a tracing member for free movement over said template, said tracing member having separate means for cooperation with each 65 of said individual patterns, an arm mounted for slidable movement sidewise of said base, linkage mechanism adjustably connecting said tracing member and said sidewise movable arm, a reproducing point for making a copy of said pattern 70 on said surface, an arm carrying said tracing member, and linkage mechanism adjustably connecting said tracing member and said reproducing

ing point for translating the forward and rearward movement of said tracing member to said reproducing point, said movable arm having sidewise movement being connected to said tracing member arm for the sidewise movement thereof. 5

9. A reproducing apparatus comprising a base 10 slideable over a surface, a pattern-carrying template mounted on said base, a tracing member for free movement over said template, an arm mounted for slidable movement sidewise of said base, a 15 slotted disc rotatably mounted in said arm, linkage mechanism connecting said tracing member and said movable arm, a reproducing point for making a copy of said pattern on said surface, an arm carrying said reproducing point, linkage 20 mechanism connecting said tracing member and said reproducing point for translating the vertical movement of said tracing member to said reproducing point, and a pin extending from said tracing member arm for engagement with the slot 25 of said disc for the horizontal movement of said latter arm and for predetermining the angularity of the reproduction.

10. A reproducing apparatus comprising a base 30 slideable over a surface, a pattern-carrying template mounted on said base, a tracing member for free movement over said template, an arm connected to said tracing member for movement in one direction across said base, an adjustable plate on said arm having an elongated slot across the 35 surface thereof, a reproducing point for making a copy of said pattern on said surface, an arm crossing said first mentioned arm and carrying said reproducing point on the free end thereof, the other end of said second mentioned arm being 40 connected to said tracing member for receiving a forward and rearward movement therefrom, and a pin on said second mentioned arm for slideable engagement with said slot for transmitting sidewise movement to said arm. 45

11. A reproducing apparatus comprising a base 50 slideable over a surface, a pattern-carrying template mounted on said base, a tracing member for free movement over said template, an arm connected to said tracing member for movement in one direction across said base, an adjustable plate on said arm having an elongated slot there-through, a reproducing point for making a copy of said pattern on said surface, an arm crossing said first mentioned arm and carrying said 55 reproducing point on the free end thereof, the other end of said second mentioned arm being connected to said tracing member for receiving a forward and rearward movement therefrom, a pin on said second mentioned arm extending through and 60 slidably engaging said slot, and a presser bar upon which said pin rests, said presser bar being compressible to lower said second mentioned arm for contact between said reproducing point and said surface for reproduction.

12. A reproducing apparatus comprising a base, a template having a plurality of contiguous zones and mounted in a fixed relation with said base, a pantograph including a fixed bearing on said base, linkage mechanism supported on said bearing and extending therefrom, a tracing member carried by said linkage mechanism and movable over said template, said tracing member having separate means for acting in each of said zones, and a reproducing point for making a copy from 70 a selected zone on a surface. 75

THEODORE J. SMULSKI.

CERTIFICATE OF CORRECTION.

Patent No. 2,035,099.

March 24, 1936.

THEODORE J. SMULSKI.

It is hereby certified that error appears in the printed specification of the above numbered patent requiring correction as follows: Page 3, second column, line 44, for "point" read member; page 4, first column, line 57, claim 7, strike out the word "second"; and line 68, claim 8, strike out the word "sidewise"; and that the said Letters Patent should be read with these corrections therein that the same may conform to the record of the case in the Patent Office.

Signed and sealed this 5th day of May, A. D. 1936.

Leslie Frazer

(Seal)

Acting Commissioner of Patents.
